KNEE TYPE MILLING MACHINE

Edward J. Kearney, Wauwatosa, Wis., assignor
to Kearney & Trecker Corporation, West Allis,
Wis.

Application October 20, 1932. Serial No. 638,667

4 Claims. (Cl. 90—18)

This invention relates to milling machines and more particularly to the type commonly known as a knee and column miller.

It is common practice to provide these machines with a primary power source consisting of an electric motor arranged to be housed within the column of the machine from which suitable transmission mechanism takes off for the driving of the spindle and for the movements of the knee, table, and saddle, and for various other purposes. As the machines have been constructed in the past, the housing of the motor within the column structure is effected by providing a chamber in the lower portion of the column structure having an opening in the rear wall sufficiently large for the motor to enter into the chamber. The opening at the rear is very objectionable for the reason that it weakens the column structure by removing metal at point where it is most required for rigidity of the structure. It results that such structures are far from being as rigid or as resistant to vibration as are structures in which the machine is driven from a suitable line shaft and pulley or in which the driving motor is housed outside the column in which event the rear wall may be substantially without openings. It is characteristic of the machines in which the motors are inserted into the column housing through the rear wall thereof that the axis of the motor shaft lies substantially parallel with the axis of the tool spindle of the machine.

It is a purpose of the present invention to provide a knee type milling machine with a prime mover consisting of a motor housed within the column while avoiding the defects above mentioned, particularly the necessity of large openings in the rear column wall.

Another object is to provide such a machine in which the openings required for inserting and removing the motor leave the front and rear walls of the column substantially intact and such openings as required are arranged along the neutral axis of the column, that is to say, a structure in which such openings as are necessary for the mounting of the motor are incorporated in the side walls of the column instead of in the rear wall, as has been the previous practice.

A further purpose is to provide a transmission for the driving of the spindle or other elements of the milling machine and originating in the shaft of a motor arranged crosswise of the column, that is to say, in a position such that the axis of the motor shaft is substantially at right angles to the axis of the milling machine spindle,

and particularly when the motor is housed within a lower portion of the column structure.

Other objects relate to the construction of the column of a machine having a driving motor housed within the column and arranged, as previously indicated, in a manner permitting a column of maximum rigidity and minimum vibration.

Other objects relate generally to improvement and simplification in the construction and operation of milling machines, particularly with respect to machines incorporating one or more of the objects previously indicated, and particularly with respect to milling machines of the type commonly called knee and column type.

A variety of other objects will be apparent from the specification.

The invention consists of the structure as herein specifically shown and claimed, together with such modifications as may be equivalent to the structure claimed.

Fig. 1 is a right side elevation of a milling machine incorporating the invention, more particularly of the column portion thereof, the table, saddle, and a portion of the knee not being shown.

Fig. 2 is a left side elevation of the same machine.

Fig. 3 is a front elevation of the column of the machine shown with the knee, table, and saddle portions removed.

Fig. 4 is a vertical section through the column showing the manner of mounting the motor therein and portions of the transmission, the section being taken on line 4—4 of Fig. 1.

Fig. 5 shows the machine partially in section taken along line 5—5 of Fig. 3.

Fig. 6 is a plan view partially in horizontal section along line 6—6 of Figs. 1 and 5, the saddle and table of the machine not being shown in this view.

The machine includes a column 1 providing a front wall 1a having guideways for the vertical movement of a knee 3, saddle 4, and table 5 shown in Fig. 5. The column also includes a rear wall 1b and side walls 1c and 1d. In the interior of the column a rib or wall 1e extends from the one to the other side wall, forming a chamber 1f housing a motor 6 having a shaft 6a projecting through an opening 7 in the side wall and carrying a pulley 8, adapted for driving a pulley 9 fixed on a main drive shaft 10, through the agency of a multiple strand belt 11.

The motor 6 is intended to be inserted within the chamber 1f through an opening 1g in the side

wall 1d, the wall 1e being extended to increase the length of the motor chamber axially of the motor shaft and the opening through which the motor is inserted being normally closed by a 5 hinged cover 12. At the other side of the column the opening 7 through the side wall 1c of the column is normally closed by a removable cover member 13 which also acts as a housing for the pulleys 8 and 9 and the belt 11. Member 13 is 10 also hinged or pivoted whereby it can be moved to expose the pulleys 8, 9 and belt 11 for inspection or repairs.

The motor 6 is supported in a manner to enable bodily adjustment in a direction adapted to determine 15 the tension on belt 11 as follows: The motor is fixed on a bracket or member 14 having a pivot 15 about which the bracket and motor may be adjusted by the means of a screw 16 and clamped in position by the means of a screw 17. The axis 20 of the pivot 15 is parallel with the axis of the motor shaft 6a.

From the shaft 10 transmission mechanism is taken off to drive the tool spindle 18 of the machine, the transmission being as follows: A shaft 23 19 coaxial with the shaft 10 may be connected or disconnected therefrom by the means of a main clutch generally denoted by the numeral 20, the clutch 20 consisting of complementary friction members adapted to be engaged or disengaged by the manual movement of a lever 21 operating through a shaft 22, levers 23, 24, a shaft 25, and a lever 26. Above and parallel with the shaft 19 is a shaft 27. A speed rate changer generally denoted by the numeral 28 provides a 30 variety of speeds between the shafts 19 and 27 by the means of the following mechanism: Fixed on shaft 27 are three differently diametered gears 29, 30, 31 adapted for engagement one at a time by complementary gears 32, 33, 34 slidably splined 40 on the shaft 19, the gears 32, 33, 34 being shiftable by the means of a hand lever 35 fixed on a shaft 36 for movement of a shaft 37 through bevel gears 38, 39, the shaft 37 having a pinion 40 engaging a suitable rack in a shifter fork 41 45 which engages the side faces of the gear 33.

The different speeds of shaft 27 are transmitted to a shaft 42 through a reverser generally denoted by the numeral 43 and consisting of a gear 44 fixed on shaft 42 and having meshed therewith a gear 45, together with a pair of gears 46-47 slidably splined on the shaft 27 and shiftable for engagement one at a time, either to engage the gear 46 to drive the gear 44 directly, or to engage the gear 47 with the gear 45 to drive the gear 44 50 reversely, the gear 45 acting as an idler. The gears 46-47 may be shifted by the means of a hand lever 48 fixed on a shaft 49 having a pinion 50 engaging a suitable rack on a rod 51 for the shifting of a fork member 52 which in part is 55 supported from the shaft 51 and in part from a rod or stud 53 and provides a fork element 54 engaging a suitable annular groove in the hub of the gear 46.

The shaft 42 drives spindle 18 through a worm 60 55 fixed on the shaft and engaging a worm wheel 56 keyed with the spindle.

Other transmission mechanism is driven from the shaft 10, including transmission mechanisms for the movement of the knee, table, and saddle, 70 whereby the table 5 may be moved in three transverse paths including longitudinal cross and vertical movements. There is intended to be incorporated in such transmission mechanisms a feed train and a quick traverse train, alternatively 75 available and each operable for the movement

of the various members, and respectively originating in the gear or element 57 which is driven from shaft 10 through the main clutch 20, and in the gear or element 58 which is driven from the shaft 10 exclusive of the main clutch 20. A variety of such transmission mechanisms is well known, together with control mechanism therefor. One of many examples of such transmission and control mechanism may be found in the application, Serial No. 586,561, filed January 14, 1932, but this is by no means to be considered as illustrative of anything other than one of a great number of mechanisms which might be used for the purpose, while carrying out the purposes previously explained.

I claim:

1. A milling machine of the nature disclosed including a column having a front wall, a substantially closed rear wall, and a plurality of side walls, a knee slidably guided for vertical movement adjacent said front wall, some of said walls together with other walls of said column providing a motor chamber at a lower column level, a tool spindle rotatably supported from said column and journaled at its opposite ends in said front and rear walls, a motor housed within said motor chamber and providing a motor shaft substantially at right angles to the axis of said spindle, and transmission mechanism connecting said motor shaft for rotation of said spindle and including a rate changer, said motor chamber and spindle supporting portions of said column being integrally formed.

2. In a milling machine of the nature disclosed, the combination of a column providing a front wall, a rear wall, and a plurality of side walls, a knee, table, and saddle slidably guided adjacent said front wall for unitary bodily vertical movement, a tool spindle rotatably supported from said column and journaled at opposite ends thereof in said front and rear walls, said column providing integrally joined portions forming an upper chamber and a lower chamber, said lower chamber being substantially solidly closed in the direction of said rear wall and in the direction of said front wall and providing an opening through one of said side walls for the admission of a motor into said lower chamber, and a transmission mechanism for said spindle including a motor in said lower chamber and 120 gearing within said upper chamber.

3. In a milling machine of the nature disclosed, the combination of a column providing a front wall, a substantially closed rear wall, and a plurality of side walls, a knee, a table, and a saddle 130 slidably guided for unitary vertical movement adjacent said front wall, a tool spindle rotatably supported from said column and journaled at its opposite ends in said front and rear walls, transmission mechanism for rotation of said spindle 135 including a shaft rotatably supported from said column below said spindle and axially at right angles thereto, a driven member fixed on said shaft, a motor housed within a lower portion of said column and providing a shaft axially parallel with the first named shaft, a driving member fixed on said motor shaft, and drive means connecting said members, said motor being supported for bodily adjustment in a direction substantially at right angles to the axis of said spindle whereby to adjust the relative position of said driving and driven members, said motor housing and spindle supporting portions of said column being integrally formed.

4. In a milling machine of the nature disclosed,
